UNITED STATES PATENT OFFICE.

CARL G. AHLENIUS, OF ZIM, MINNESOTA.

GAME APPARATUS.

1,207,462.

Specification of Letters Patent.

Patented Dec. 5, 1916.

Application filed August 16, 1916. Serial No. 115,283.

To all whom it may concern:

Be it known that I, CARL G. AHLENIUS, a citizen of the United States, residing at Zim, in the county of St. Louis and State 5 of Minnesota, have invented certain new and useful Improvements in Game Apparatus, of which the following is a specification.

This invention relates to a game and more 10 particularly to an amusement device consisting of an amusing and interesting apparatus from which both pleasure and knowledge of historical events can be derived.

The above and additional objects are accomplished by such means as are illustrated 15 in the preferred embodiment and in the accompanying drawings, wherein like characters denote like or corresponding parts throughout the several views, in which:

20 Figure 1 is a side elevation. Fig. 2 is an elevation of the opposite side. Fig. 3 is a top plan.

A base 1 is constructed of a rectangular piece of any suitable material and is provided 25 with the upstanding supporting standards 2 which are provided with slots 3 in their upper ends for the reception of the pintles 4 which are formed at the end of a supporting shaft. A cylindrical drum 30 5 is secured to the shaft and is thereby supported for rotary movement on the pintles 4. Fastened to one of the pintles is a knob 6 which may be grasped by the fingers to impart a rotary motion to the drum by 35 simply twisting the knob 6.

The drum is provided with a circular end 7 and a similar end 8. Any suitable material of light weight may be employed in constructing the drum and the end 7 is 40 graduated into a number of equally spaced divisions which are provided with numerals as shown by Fig. 1 of the drawing. The opposite face 8 of the drum is also divided, as shown by Fig. 2 of the drawing, and carries 45 a plurality of numerals placed adjacent the edge of the circular end 8 and chosen at random from the numbers between one and one hundred. Below each of these last mentioned numerals on the end 8, is inscribed 50 a suitable phrase pertaining to the rules governing the manner of playing the game.

Mounted upon the base-board is an indi-

cator arm 9 which is provided with indicator fingers 10 and 11 which overlie the 55 ends 7 and 8 of the drum and register with the numerals inscribed thereon.

In operating the device for playing the game, any number of players may be accommodated. The first player grasps the 60 knob 6 and gives the drum a quick turn by twisting the knob 6. When the drum comes to a stop the indicator finger 11 will point to a certain numeral on the end 7 whereupon the player marks that numeral upon 65 a score sheet. The other players then proceed to rotate the drum in turn until each has procured a starting number. The first player again rotates the drum and adds the number obtained, when the drum stops, to 70 the number already placed under his name on the score sheet and proceeds in this manner until one of the players has totaled a hundred, this player then being declared the 75 winner. In order that the game may become more interesting, however, the players, after each addition, must compare that total with the numerals on the end 8 of the drum and should the total tally with any of these numbers, the player must proceed according to the instructions inscribed under 80 the number. For instance, assuming that the first player obtains a total of 29 after three turns of the drum. It will be noted that under the numeral 29 on the end 8 of 85 the drum the instructions read; "Add nothing until you get odd numbers." The player, therefore, is not permitted to add any number to his total until he has first obtained an odd number by rotating the 90 drum whereupon, he will proceed in the usual manner. Any of the other totals obtained by the players must also be compared with the numbers on the end 8 of the drum for obtaining instructions as to the next 95 method of procedure.

It will be noted, by referring to Fig. 3 of the drawing that the periphery of the drum contains a number of divided spaces in which are printed a series of historical 100 events, such as the names and dates of famous battles and other similar interesting historical events. Other useful information may be also printed on the drum such as the dates of the most prominent holidays in 105 the United States; the differences in time

between Washington and various large cities of the world, and other similar interesting and instructive information.

I claim:

5. 1. A game apparatus comprising a rotatable drum, each circular end of which is provided with a plurality of numbers, indicator fingers adapted to register with the numerals on each end of said drum, one 10 end of the drum having a plurality of instructive phrases inscribed for use in conjunction with certain of the said numerals.
15. 2. A game apparatus comprising a supporting structure, a rotatable drum having oppositely extending trunnions engaged with the said supporting structure, each end of the drum provided with a plurality of numbers, indicator fingers adapted to register with the numerals on each end of said 20 drum, one end of the drum having a plurality of instructive phrases inscribed for use in conjunction with certain of the said numerals.
25. 3. A game apparatus comprising a supporting structure, including a pair of uprights having vertical slots provided in their upper ends, a rotatable drum provided with trunnions extending from the center of each end of the drum and disposed in the said slots, an indicator arm carried by 30 the supporting structure, indicator fingers

formed on the terminal of the indicator arm, one indicator finger being adapted to register with the edge of each circular end of the drum, and a plurality of numerals 35 inscribed upon each end of the drum.

4. A game apparatus comprising a supporting structure, including a pair of uprights having vertical slots provided in their upper ends, a rotatable drum provided 40 with trunnions extending from the center of each end of the drum and disposed in the said slots, an indicator arm carried by the supporting structure, indicator fingers 45 formed on the terminal of the indicator arm, one indicator finger being adapted to register with the edge of each circular end of the drum, a plurality of numerals inscribed upon each end of the drum, the numerals on one end being arranged in 50 numerical order while the numerals on the opposite end are chosen and inscribed at random, the last mentioned end of the drum being also provided with a plurality of instructive phrases inscribed for use in conjunction with the said numerals. 55

In testimony whereof I affix my signature in presence of two witnesses.

CARL G. AHLENIUS.
